United States Patent Office

Des. 179,657
Patented Feb. 5, 1957

179,657

PISTOL

Harvey T. Pittman, Jr., Tarboro, N. C.

Application March 18, 1955, Serial No. 35,094

Term of patent 14 years

(Cl. D30—1)

FIG. 1

FIG. 2

I claim:

The ornamental design for a pistol, as shown.
